PRINTING APPARATUS

Joseph Sinkovitz, Pittsburgh, Pa., assignor to
Miller Printing Machinery Co., Pittsburgh, Pa.,
a corporation of Pennsylvania

Application January 21, 1941, Serial No. 375,131

8 Claims. (Cl. 101—390)

This invention relates to printing apparatus and particularly to chases for use with bed and cylinder presses. The invention relates more particularly to a chase which has as parts there-

5 bearers for cooperation with the cylinder bearers on a printing stroke. The invention will be described as embodied in printing apparatus of the flat bed and cylinder type. As well known in the art, the bed and cylinder normally carry bearers which ride upon each other during the printing stroke to insure proper positioning and driving of the members of the printing couple during the actual printing operation. Ordinarily the bed bearers are 10 screwed or otherwise relatively permanently fastened to the press bed and are considered to be a part of the bed proper. The printing form is locked up in a chase and the chase with the form locked therein is transferred to the bed and placed upon the bed between the bed bearers and fastened in place for printing. With this 15 standard type of construction the transverse dimension of the form is undesirably limited since the chase including its longitudinally extending bars must fit between the bed bearers. Consequently the transverse dimension of the form must be less than the transverse dimension between the inner vertical faces of the bed bearers by at least twice the width of the longitudinally 20 extending chase bars.

The undesirability of thus limiting the transverse dimension of the form has long been appreciated. Attempts have been made to increase the transverse dimension of the form relatively to that of the bed by eliminating the use of a chase and locking up the form between the bed bearers and transversely extending bars on the bed. While this enables a wider form to be used, since it eliminates the longitudinally extending chase bars which in the standard construction lie between the bed bearers and the form, it is necessary to make up the form on the bed, which from the practical standpoint is virtually impossible, as printing establishments are not arranged to enable this to be done; moreover, it is very inconvenient to set up a form on a press bed, and furthermore the compositor working on the form and the form itself in the process of being set up on the bed interfere with work on the press during the time of setting up the form. The fact is that the proposals to make up the form on the press bed and lock it in between the bed bearers and transversely extending bars on the bed is utterly impractical and never went into general use. Instead the art has continued to restrict

10 the transverse dimension of the form by employing a chase adapted to be transferred to the press bed with a form locked up therein and positioned upon and fastened to the press bed between the bed bearers. This has been appreciated by those skilled in the art to be undesirable because of the restriction imposed with respect to the transverse dimension of the form, but no practicable solution to the problem has been found prior to the present invention.

15 I obviate all of the disadvantages of the prior art and provide for a form of the maximum width relative to the width of the bed, yet which may be set up on the usual table employed for that purpose and then locked in a chase and when so locked transferred in the chase to the press bed. I preferably do away with the bed bearers screwed or otherwise more or less permanently fastened to the bed and I form the chase with 20 bearers adapted to cooperate with the cylinder bearers on a printing stroke. Thus the full width of the bed except for the transverse dimensions of the longitudinally extending chase bars may be used for the form. No change in 25 the standard mode of setting up the form is required. This is done on the usual table removed from the press so that work may be done on the press without interference while the form is being set up. Means are provided for fastening the 30 chase to the bed in proper position so that the bearers which form part of the chase and which take the place of the standard bed bearers will properly cooperate with the cylinder bearers on a printing stroke. The chase is preferably fastened to the bed by means cooperating with the 35 end portions of the chase. It is not necessary to screw down the bearers or any part of the chase.

40 Other details, objects and advantages of the invention will become apparent as the following description of a present preferred embodiment thereof proceeds.

In the accompanying drawings I have shown a present preferred embodiment of the invention, in which

45 Figure 1 is a plan view with portions cut away of a press bed with a chase fastened thereto, no form being shown in the chase in order to more clearly show features of the construction;

50 Figure 2 is a vertical longitudinal cross-sectional view to enlarged scale and with a portion cut away taken on the line II—II of Figure 1;

55 Figure 3 is a vertical transverse cross-sectional view to enlarged scale and with a portion cut away taken on the line III—III of Figure 1 and showing the bed with the chase thereon and also

showing fragmentarily the cylinder which is omitted in Figure 1;

Figure 4 is a plan view of the chase with portions cut away;

Figure 5 is a vertical longitudinal cross-sectional view to enlarged scale taken on the line V—V of Figure 4; and

Figure 6 is a vertical transverse cross-sectional view to enlarged scale taken on the line VI—VI of Figure 5.

Referring now more particularly to the drawings, there is shown a bed of a flat bed and cylinder press, the bed being designated generally by reference numeral 2. The bed shown is made of aluminum alloy, although the invention is not limited with respect to the particular material or structure of the bed. A steel surface plate 3 lies upon the central portion of the bed and is screwed or otherwise fastened thereto. At the longitudinal edges of the bed are steel strips 4 which are of the same thickness as the plate 3 and to all intents and purposes form lateral continuations of the plate 3.

The bed 2 is a standard bed except that in place of the strips 4 permanently attached bed bearers have been employed prior to the present invention. I eliminate these permanently attached bed bearers since, as above explained, I form my chase with bearers which on a printing stroke cooperate with the cylinder bearers. The strips 4 are employed to cooperate with the plate 3 to provide the bed with a continuous flat working surface. In place of using separate strips 4 I may widen the plate 3 to the full width of the bed. The cylinder forming the cooperating member of the printing couple is shown at 2a in Figure 3. It will be understood that the cylinder cooperates with the bed in the usual way except that the bearers on the bed with which the cylinder bearers 2b contact on a printing stroke are part of the chase now to be described.

The chase is designated generally by reference numeral 5. It comprises longitudinal bars 6 and transverse bars 7. The bars 6 and 7 are preferably more or less permanently connected together to form a permanent chase and the bars 6 and 7 may be welded or screwed together or otherwise suitably fastened together. The bars 6 are adapted to extend longitudinally of the bed, that is, in the direction of movement of the bed during printing. The bars 7 extend transversely of the bed. The width of the chase between the outer faces of the bars 6 is preferably equal to the width of the bed so that when the chase is laid upon the bed it covers the full width of the bed.

The longitudinal chase bars 6 are designed and machined to serve as bearers functioning as do bed bearers to cooperate with the cylinder bearers 2b in operation of the press. Each of the bars 6 has a plane machined central portion 8 adapted when the chase is applied to the bed to lie in a plane parallel to the plane of movement of the bed and inclined end approach portions 9 to insure bringing of the cylinder bearers 2b into proper cooperative relationship with the portions 8 of the bed bearers upon operation of the press without undesirable jarring.

Means are preferably provided for fastening the chase in proper position on the bed whereby the chase may be fastened to and unfastened from the bed very quickly. To this end the bed is provided with a transverse bar 10 against which the front bar 7 of the chase is adapted

to abut, the bed bar 10 having at its center an undercut portion 11 of limited length transversely of the bed. The front bar 7 of the chase has at its outer or forward edge a projection 12 of generally triangular cross-sectional form as shown in Figures 2 and 5, which projection is adapted to enter the recess or undercut portion 11 in the bed bar 10. The transverse dimension of the portion 12 is such that it snugly fits transversely within the recess 11 whereby to center the chase on the bed. Moreover, since the portion 12 underlies part of the bed bar 10 when the chase is in place on the bed it holds down the front edge of the chase and insures that it will remain in proper relationship to the bed during operation of the press. The angular alignment of the chase relatively to the bed is provided for by abutment between the front bar 7 of the chase and the bed bar 10. The chase is held forward against the bed bar 10 by the usual clamps 13 connected with the bed and bearing against the rear chase bar 7.

Thus I provide printing apparatus enabling the printer to employ a form of the maximum width relatively to the width of the bed but without necessitating setting up the printing form on the bed. Thus is solved a problem which has long existed in the art and the only attempted solution of which, so far as I am aware, has been to utilize the permanently attached bed bearers together with transverse bars on the bed in place of a chase, necessitating setting up of the form on the bed.

While I have shown and described a present preferred embodiment of the invention it is to be distinctly understood that the invention is not limited thereto but may be otherwise variously embodied within the scope of the following claims.

I claim:

1. Printing apparatus for a printing press whereby a form may be made up off the press bed and as made up transferred to the bed yet the full width of the bed may be effectively utilized, comprising a bearer chase having longitudinally extending bars and means connecting said bars together in fixed relationship so that the chase with a form made up therein may be transferred to and from the bed, the outer edges of said longitudinally extending bars being spaced apart a distance approximating the full width of the bed, the inner edges of said bars defining the lateral limits of the form and the width of said bars approximating the width 55 of the bearers of the member of the printing couple cooperating with the bed during printing, said bars constituting the bed bearers of the printing apparatus and engaging the bearers of the member of the printing couple cooperating with the bed during printing.

2. Printing apparatus for a printing press whereby a form may be made up off the press bed and as made up transferred to the bed yet the full width of the bed may be effectively utilized, comprising a bearer chase having longitudinally extending bars and means connecting said bars together in fixed relationship so that the chase with a form made up therein may be transferred to and from the bed, the outer edges of said longitudinally extending bars being spaced apart a distance approximating the full width of the bed, the inner edges of said bars defining the lateral limits of the form and the width of said bars approximating the width of the bearers of the member of the printing cou-

ple cooperating with the bed during printing, said bars constituting the bed bearers of the printing apparatus and engaging the bearers of the member of the printing couple cooperating with the bed during printing, and means cooperating with the ends of the chase for holding the chase in place on the bed.

3. Printing apparatus for a bed and cylinder press whereby a form may be made up off the bed and as made up transferred to the bed yet the full width of the bed may be effectively utilized, comprising a bearer chase having longitudinally extending bars and means connecting said bars together in fixed relationship so that the chase with a form made up therein may be transferred to and from the bed, the outer edges of said longitudinally extending bars being spaced apart a distance approximating the full width of the bed, the inner edges of said bars defining the lateral limits of the form and the width of said bars approximating the width of the cylinder bearers, said bars constituting the bed bearers of the printing apparatus and on the printing stroke engaging the cylinder bearers and driving the cylinder therethrough.

4. Printing apparatus for a bed and cylinder press whereby a form may be made up off the bed and as made up transferred to the bed yet the full width of the bed may be effectively utilized, comprising a bearer chase having longitudinally extending bars and means connecting said bars together in fixed relationship so that the chase with a form made up therein may be transferred to and from the bed, the outer edges of said longitudinally extending bars being spaced apart a distance approximating the full width of the bed, the inner edges of said bars defining the lateral limits of the form and the width of said bars approximating the width of the cylinder bearers, said bars constituting the bed bearers of the printing apparatus and on the printing stroke engaging the cylinder bearers and driving the cylinder therethrough, and means cooperating with the ends of the chase for holding the chase in place on the bed.

5. Printing apparatus comprising a printing couple and a bearer chase adapted to lie on the bed of the printing couple, the bearer chase having longitudinally extending bars and means connecting said bars together in fixed relationship so that the chase with a form made up therein may be transferred to and from the bed, the outer edges of said longitudinally extending bars being spaced apart a distance approximating the full width of the bed, the inner edges of said bars defining the lateral limits of the form and the width of said bars approximating the width of the bearers of the member of the printing couple cooperating with the bed during printing, said bars constituting the bed bearers of the printing apparatus and engaging the bearers of the member of the printing couple cooperating with the bed during printing, whereby a form may be made up off the bed and as made up transferred to the bed yet the full width of the bed may be effectively utilized.

6. Printing apparatus comprising a printing couple and a bearer chase adapted to lie on the bed of the printing couple, the bearer chase having longitudinally extending bars and means connecting said bars together in fixed relationship so that the chase with a form made up therein may be transferred to and from the bed, the outer edges of said longitudinally extending bars being spaced apart a distance approximating the full width of the bed, the inner edges of said bars defining the lateral limits of the form and the width of said bars approximating the width of the bearers of the member of the printing couple cooperating with the bed during printing, said bars constituting the bed bearers of the printing apparatus and engaging the bearers of the member of the printing couple cooperating with the bed during printing, whereby a form may be made up off the bed and as made up transferred to the bed yet the full width of the bed may be effectively utilized, and means cooperating with the ends of the chase for holding the chase in place on the bed.

7. Printing apparatus comprising a cooperating bed and cylinder forming a printing couple and a bearer chase adapted to lie on the bed, the bearer chase having longitudinally extending bars and means connecting said bars together in fixed relationship so that the chase with a form made up therein may be transferred to and from the bed, the outer edges of said longitudinally extending bars being spaced apart a distance approximating the full width of the bed, the inner edges of said bars defining the lateral limits of the form and the width of said bars approximating the width of the cylinder bearers, said bars constituting the bed bearers of the printing apparatus and on the printing stroke engaging the cylinder bearers and driving the cylinder therethrough, whereby a form may be made up off the bed and as made up transferred to the bed yet the full width of the bed may be effectively utilized.

8. Printing apparatus comprising a cooperating bed and cylinder forming a printing couple and a bearer chase adapted to lie on the bed, the bearer chase having longitudinally extending bars and means connecting said bars together in fixed relationship so that the chase with a form made up therein may be transferred to and from the bed, the outer edges of said longitudinally extending bars being spaced apart a distance approximating the full width of the bed, the inner edges of said bars defining the lateral limits of the form and the width of said bars approximating the width of the cylinder bearers, said bars constituting the bed bearers of the printing apparatus and on the printing stroke engaging the cylinder bearers and driving the cylinder therethrough, whereby a form may be made up off the bed and as made up transferred to the bed yet the full width of the bed may be effectively utilized, and means cooperating with the ends of the chase for holding the chase in place on the bed.

JOSEPH SINKOVITZ.
